*Inventor,
Garnett January*

UNITED STATES PATENT OFFICE.

GARNETT JANUARY, OF WASHINGTON, DISTRICT OF COLUMBIA.

COMBINED TABLE AND LAMP STANDARD.

Application filed March 21, 1924. Serial No. 700,850.

To all whom it may concern:

Be it known that I, GARNETT JANUARY, a citizen of the United States, residing at Washington, in the District of Columbia, have invented a new and useful Piece or Article of Furniture, More Specifically a Combined Table and Lamp Standard, of which the following is a specification, reference being had to the accompanying drawing, which is made a part of the same.

The object of the invention is to produce an article of furniture which will serve the two-fold purpose of a table or a book case or book-shelves and a lamp standard. Further, to provide such a device of simple and cheap construction which will be neat and attractive in appearance.

To attain the desired objects the invention may be stated, briefly, consists in having one or more of the supporting legs of the table or book shelf extend above the top thereof or to a sufficient height to constitute a lamp standard or provide a support for lighting fixtures. This object is attained by having this leg, or these legs, secured to or near the edge of the table or shelf. The table may consist of a top with or without a number of shelves, and be of any shape convenient to the uses and artistic development of this piece of furniture. This combined table or book shelf and lamp-standard may be either of wood or other material, and the leg or legs constituting the lamp-stand or standards are either hollow in part to receive circuit wires, gas pipes, or the like, or may be made solid as is best adapted to the lighting fixture which is intended to attach as well as to provide and to secure ample supporting and balancing means for said table or book shelf.

In the drawing illustrating selected embodiments of my invention:

Fig. 1 is a perspective view of a combined table and lamp standard showing a triangular top.

Fig. 2 a perspective of a table showing a semicircular or curvilinear top, 2^a, and shelf, 3^a, combined with an extended lamp supporting standard, and

Figs. 3 and 4, similar views of a book case or book shelves preferably having rectangular tops and shelves each with a pair of lamp standards.

In the embodiments of my invention with the triangular or semi-circular top and the bookshelf having a lamp standard that if

desired is to be placed against the wall and would cause the shade to strike the wall, it is contemplated to bend the top portion of the standard in or to provide an offset portion for the shade support as by means of pipe like a hollow crank shaft or bell crank lever either as a conduit for the electric wires or as an extension of the gas pipe.

With reference to these views—

In Figure 1, the table 1 has a triangular shaped top member 2 and shelf 3, supporting legs 4 and 5 secured thereto in any preferred manner, the balancing and supporting leg 5 extending upward or projecting above the table top at 6, a sufficient height to form and constitute a lamp standard for the usual lamp and shade preferably for those of the electric type.

In Figure 2, the same general structure is provided and is shown as adapted to a semi-circular type of table top and shelf, the extended leg rigidly secured on the outside of the semi-circle and with one shelf below also secured to said leg. This type is especially adapted for use at the end of a couch or settee.

Figure 3 is an adaptation of my combined leg and standard to a book case comprising a number of book shelves, two of the legs, 5^a, extending upward to form an artistic lamp standard 6, for lamp shades and lamp 7, said standards being of any desired design.

In Figure 4 is shown another selected embodiment which I have found useful, differing from Figure 3 in that the extended legs constituting the lamp standards 5^b are both placed at the front instead of at the opposite diagonal corners, front and back, as in Figure 3.

My invention also contemplates the adaptation of the combined supporting leg and lamp standard to the usual type of rectangular card tables which it is not considered necessary to illustrate since it differs only from the structure shown in Figures 1 and 2 in the shape of the top.

These lamp standard legs are preferably made hollow or bored to receive, house, and cover or protect the electric wires or connections for an electric lamp or for gas pipes if a gas lamp is used and as is indicated by dotted lines at 8. The bore of the leg and standard may extend clear through the lower end of the leg or at least to an opening 9 adapted to receive the usual socket for the plug of a connecting cord, the con-

necting wires within the leg remaining permanently in place. These features are illustrated in Figure 3, but it is understood that such construction is characteristic of all these combinations of lamp-standards and table or the like. Such combinations as shown thus provide and I claim an economy of space, convenience, and simplicity of construction especially desirable in apartments through applicable elsewhere, and they are all characterized by the fact that one or more of the supporting legs extend upward to form a lamp-stand, standard or standards.

Having thus fully described my invention, I claim:

1. As a new article of manufacture, a horizontal top member, having a plurality of supporting legs secured thereto, one leg of which extends upward above said member to provide and constitute a supporting standard for lamp fixtures.
2. As a new article of manufacture, a

combined table and lamp standard comprising a horizontal top and a plurality of supporting legs, one or more of said legs extending above said top to constitute a lamp standard or standards, substantially as shown and described.

3. A new article of manufacture, comprising a plurality of horizontal members, each adapted to receive and support articles placed thereon, a plurality of supporting legs at one side thereof and one or more additional supporting legs spaced therefrom to balance and support said members, said members being secured thereto and one or more of said additional legs extending above the upper end of said members to provide and constitute a standard or standards for a lamp fixture or fixtures, substantially as shown and described.

In testimony whereof I affix my signature.

GARNETT JANUARY.
